Primary Examiner — Eric Goodman*Assistant Examiner* — Sanjeev Paul(57) **CLAIM**

I claim the ornamental design for a neck pillow, as shown and described.

DESCRIPTION

FIG. 1 is a perspective view of a neck pillow, showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top elevational view thereof; and,

FIG. 7 is a bottom elevational view thereof.

It is certified that error appears in the above-identified patent and that said Letters Patent is hereby corrected as shown below:

On the Title Page

Item (71) should read:

-- Applicant: Congyu CHEN, Shenzhen (CN) --

Item (72) should read:

-- Inventor: Congyu CHEN, Shenzhen (CN) --

Item (73) should read:

-- Shenzhen Lian Da Sponge Product Co., Ltd --
